PACKAGING CONTAINER FOR SEWING IMPLEMENT

Edmund A. Kustusch, 581 Fiske Drive,
Detroit, Mich. 48214

Filed May 10, 1971, Ser. No. 142,086

Term of patent 14 years

Int. Cl. D9—03

U.S. Cl. D9—172

FIG. 1 is a top perspective view of a packaging container for sewing implements, in an open position, showing my new design;

FIG. 2 is a front elevational view showing the design in a closed, upright position;

FIG. 3 is an elevational view looking from the right of FIG. 2;

FIG. 4 is an elevational view looking from the left of FIG. 2;

FIG. 5 is a rear elevational view;

FIG. 6 is a top plan view; and

FIG. 7 is a bottom plan view thereof.

I claim:

The ornamental design for a packaging container for sewing implements, as shown and described.
